UNITED STATES PATENT OFFICE.

MAX MAAG, OF SCHWAMENDINGEN, SWITZERLAND.

ORGAN ACTION.

Application filed August 17, 1923. Serial No. 657,910.

The present invention relates to a pneumatic and electro-pneumatic actuating mechanism for musical instruments equipped with pneumatic tone-producers, and its principal object is to regulate the tone power or loudness of these tone-producers by varying the wind pressure supplied thereto according to the will of the player.

The present invention may be used with any tone-producer, the pitch of which remains constant with varying wind pressure. It is well known that certain reeds and pipes, either of special form or equipped with compensating devices, maintain a constant pitch for varying pressures of air to which my invention is applicable.

Another principal object of the present invention is to provide a construction permitting the operator to vary the tone intensity or loudness of any individual pipe or reed by varying the degree of pressure upon the key by means of which that pipe or reed is played.

Another object of the invention is to provide means to supply wind directly to the tone-producers at any desired pressure over a wide range by varying the pressure upon the keys.

Another object of the invention is to dispose the valve in the wind supplying mechanism for the tone-producers so that the pressure within the chest directly associated with the tone-producer may be varied, and also to so position the pallet that it will open into this chest directly adjacent the tone-producer.

Another object of the invention is to provide a pressure regulating device operated by depressing the keys so that the pressure admitted to the tone-producers connected with that key may be directly controlled and the intensity of its tone widely varied.

Another object of the invention is to attach pneumatically or electrically controlled means to the tone-producer pallets so that these pallets may be automatically controlled to vary their opening and also control the pressure of air supplied to its tone-producer.

With these and other objects in view, my invention consists in the features of construction and operation set forth in the following specification and illustrated in the accompanying drawings.

In the accompanying drawings annexed hereto and forming a part of this specification, I have shown my invention embodied in organs having pneumatic and electrical

means for controlling the wind pressure supplied to the tone-producers. It will be understood, however, that certain features of the invention can be otherwise embodied and adapted for other types of instruments and that the drawings are not to be construed as defining or limiting the scope of the invention, the claims appended to this specification being relied upon for that purpose.

In the drawings:

Figure 1 is a cross sectional view through the keyboard and wind chest of an organ.

Fig. 1^a is a view of a detail.

Fig. 2 is a plan view of the parts shown in Fig. 1, portions being broken away showing sections taken upon lines A—A and B—B of Fig. 1.

Fig. 3 is a view similar to Fig. 1 showing a pneumatic relay mechanism for controlling the wind pressure admitted to the tone-producer, and

Fig. 4 shows electro-pneumatic means for controlling the wind pressure.

In the above mentioned drawings, I have shown several embodiments of the invention which are now deemed preferable, but it is to be understood that changes and modifications may be made within the scope of the appended claims without departing from the spirit of the invention.

Briefly, my invention in its broadest aspect comprises the following principal parts: First, a keyboard, the keys of which are resiliently supported at one end so that they may be depressed different amounts by applying different amounts of pressure thereto; second, pneumatic or electrical means controlled thereby so that when the key is depressed these will be actuated to vary a pressure control mechanism; third, a source of air under pressure; fourth, a wind chest, the pressure in which is regulated by the position of the pneumatic or electric means; fifth, a wind chest having a bellows therein; sixth, a pallet opening into a wind chest directly associated with the tone-producers; and seventh, pneumatic or electrical means connecting the last named pallet with said bellows to control the pressure of air supplied to said tone-producer.

Referring more in detail to the figures of the drawings, and particularly to Figs. 1, 2 and 3, I provide a wind chest 1 which may be filled with air under pressure by any suitable means through opening 2. The pres-

sure of this air within this chest 1 may be indicated by p . In the upper surface of this chest is formed an opening 3 which may be closed by a pallet 4 opening within the chest 1. The opening 3 extends into a second wind chest 5, the upper surface of which is also provided with an exhaust opening 7 which may be closed by pallet 8. The pallets 4 and 8 are connected together by a suitable wire 9 so that but one of these pallets can be closed at any one time. The closing of one pallet serves to open the other one. At the upper end of the wire, connecting means are carried, to which a key 11 may be fastened.

Key 11 is preferably pivotally mounted at 12 and is supported at its playing end by a light compressive spring 14. While key 11 is not being played, the pallet 4 rests against its opening 3 by reason of the pressure of the air within chest 1 and of spring 14. The opening 3 is therefore maintained closed and the exhaust opening 7 entirely open. If pressure is placed upon the key 11, the air pressure supporting pallet 4 is overcome and spring 14 is compressed so that the pallet 4 opens and the pallet 8 entirely closes. With the pallets 4 and 8 in these positions air rushes from the wind chest 1 to the chest 5 where it will develop a pressure equal to p . If, however, key 11 is not pressed to its lowermost position to entirely close pallet 8, compressed air not only enters chest 5 but the air within chest 5 may pass out through opening 7 to atmosphere under a certain pressure p_1 . For the calculation of the latter it may be considered that the amount of air being exhausted from the chest 5 equals the amount of air admitted.

Taking the product of the openings and the difference of air pressures between the adjacent chests as a measure for these amounts of air, we may obtain the following equation:

$$I(b + p - (b + p_1)) = O(b + p_1 - b)$$

in which

I = the area of inlet opening 3

O = the area of outlet opening 7

b = the pressure of the atmosphere

p = the air pressure in wind chest 1

p_1 = the air pressure within the chest 5.

It is this last factor which we wish to obtain. From the above equation we may obtain the following:

$$I(p - p_1) = O(p_1)$$

$$I \cdot p = (O + I)p_1 \text{ and}$$

$$p_1 = p \cdot \frac{I}{O + I} \text{ and}$$

$$p_1 = p \cdot \frac{I}{I + O}$$

In other words, pressure p_1 within chest 5

for a given pressure p in chest 1 depends entirely upon the relation of the free areas of the openings 3 and 7, which depend upon the positions of the pallets 4 and 8. As can be readily seen, the variation of the relative positions of the pallets 4 and 8 and therefore

the relation $\frac{O}{I}$ rests entirely with the will of the player. When the pallet 4 is entirely closed then $\frac{O}{I}$ equals infinity, in which case p_1 will equal zero. When pallet 8 is entirely closed then $\frac{O}{I}$ will equal zero, in which case

p_1 will equal p . When $O = I$, then $\frac{O}{I} = 1$ and

$p_1 = \frac{1}{2} p$. Therefore by supplying pressure to key 11 to a greater or less extent, the pressure within the chest 5 may be varied to any desired pressure from zero up to the pressure p supplied by the pump to the chest 5. The above described valve mechanism comprises a pressure regulating valve and, by varying the position of the key, widely varying pressures can be obtained within the chest 5. By increasing the pressure on key 11, its position is varied to open the pallet 4 to a greater extent and thus increase the pressure within chest 5. Also, as soon as the pressure upon the key 11 is released to any extent, the key moves upward, thus serving to move the pallet 4 to its closed position and thus reducing the pressure within the chest 5.

Also shown in Fig. 1 is a section through the respective chests of an instrument having three sets of tone-producers of different character. This wind chest shown diagrammatically comprises a box 15 divided into upper and lower chests by a horizontal partition 16. The lower space or chest contains walls 17 and 18 dividing it into three independent spaces forming the wind tunnels for the three sets of tone-producers. The strips 17 and 18 also extend through the upper portions of the wind chest 15. This upper wind chest, it will be understood, is divided rectangularly by means of partitions into as many independent chest or spaces for each register or stop as there are keys in the keyboard, several of these being shown in Fig. 2. Above these upper chests, the tone-producers are placed as will be understood by reference to Figs. 1 and 2. These are of successively higher pitch corresponding to the different keys on the keyboard.

Assuming that the wind tunnels 23—28, etc., are filled with compressed air from any suitable source, the tone-producers of the pitch corresponding to the key 11 will sound while that key is depressed. The tone-producers will not, however, sound when the wind tunnels are closed and therefore do not contain the compressed air. As the means for supplying pressure to the tunnels 23—28,

etc., form no part of the invention, they have not been described.

The explanation of the operation will be confined to the operation of a tone-producer

5 21 shown directly attached to the chest 20, shown in Figs. 1 and 2. This chest 20 is connected with its wind tunnel 23 through an opening 22. The opening 22 is adapted to be closed by a pallet 24 so disposed that it 10 may open into the tone-producer chest 20. This pallet 24 is connected through a wire 25 to the movable portion of a bellows fitted to the lower portion of the chest or tunnel 23. The space within the bellows 26 is adapted 15 to be connected with the chest 5 of the pressure regulating device through a pipe or tube 19. In order to make use of this particular stop represented by the tone-producer 21, its tunnel or chest 23 therefore must be provided 20 with air under pressure from the source of supply, the pressure of which being p , as before. This pressure, upon one side, acts upon the movable portion of the bellows to compress it, thus giving a closing effect to 25 the pallet 24. On the opposite side, however, the pressure p acts directly upon the pallet 24 to open it. If the active surfaces of the bellows 26 and the pallet 24 were equal, then the opening and closing action upon the 30 pallet 24 would be equal and it would remain closed in spite of the chest 23 being under pressure.

As soon, however, as key 11 is depressed, air under a predetermined pressure as described 35 above is introduced within the bellows 26, this pressure acting upon the lower side of the bellows forcing it toward its open position and therefore tending to open the pallet 24, through wire 25. As soon as pallet 24 40 opens, wind enters the space 20 and thus the tone producer speaks. A certain pressure p_2 is developed within chest 20 which on one side causes a current of wind through the tone-producer 21 and to the opposite side tends to close pallet 24. This pressure may 45 be determined somewhat as follows: Pressure p from the space 23 tends to open the pallet 24 and also attempts to close the bellows thus holding the pallet 24 in one position. The 50 pressure p_1 acting within the inner side of the bellows tends to open the bellows and thus open the pallet 24. A third pressure p_2 within the chest 20 tends to close the pallet 24 as well as cause the tone-producer to speak. Setting out these forces acting upon pallet 55 24 and giving the opening pressures + and the closing pressures - signs, we get the following equation for the balance of the latter.

$$+p - p + p_1 - p_2 = 0,$$

or, in other words, $p_2 = p_1$.

In other words, under any circumstances, the pressure developed within the tone-producer chest 20 cannot be higher or lower but 60 automatically is always the same as that with-

in the chest 5 of the pressure regulating device. This, as we have seen above, may be regulated by applying more or less pressure to the key 11.

The pipe or tube 19 from each of the keys 70 11 not only extends to a single bellows 26 but at the same time extends to other bellows 27 which are mounted within the register tunnel 28 of a separate type of tone-producer indicated at 29. If this register during operation is not to be sounded, its register tunnel 28 may be closed so that no air under pressure may enter it. The pressure p_1 within pipe 19 entering bellows 27 opens the pallet 30, but in spite of this, with register tunnel 28 closed from its supply of compressed air, the tone-producer 29 will not sound.

The above described mechanism it will be noted, is very similar to that which is well known and used in organ building. It is known as a "pneumatic tracker action". The principal distinction, however, of the present mechanism over those previously known and used is that pallet 24, and those similar thereto for the different tone-producers, open directly into the tone-producer chests 20 whereas in the ordinary organ, the tone-producer pallets open always into the chest or tunnel 23, that is, in the opposite direction. It is this difference of position and direction of opening of the pallet 24 that permits regulating of air pressure to its tone-producer.

If pallet 24 were arranged upon the opposite side of the opening 22, as in ordinary organ construction, then there would be no possibility of regulating its opening by the counter-action of pressure p_2 . The pallet in that position could only be entirely closed or entirely open for the reason that any pressure arising within chest 20 would aid in opening the pallet 24. As soon as the opening of pallet had been accomplished by the opening of bellows 26, (connected to pallet 24 by a suitable lever arrangement) it would be held in its open position. On the other hand, pallet 24 would close instantly when the pressure was exhausted from the bellows 26 and the pressure within the tunnel 23 alone acted upon the pallet. If, however, a tone-producer is applied the pitch of which does not alter with different pressures of wind supplied to it so that it may be played at any pressure to vary its loudness, then a construction must be made use of which allows regulating the pressure and therefore the opening of the pallet 24 to any desired degree. This is only possible when the pressure generated within the tone-producer chest 20 counteracts the opening forces of pallet 24 until a balance between the closing and opening forces for any pressure p_1 in bellows 26 is reached.

It will be seen from the above that the pressure within the chest 20 always equals the pressure within the chest 5 of the pressure regulating device. This not only makes

100

105

110

115

120

125

130

it possible to sound the tone-producer at any desired degree of power but also enables one to increase or decrease the tone power or loudness of the tone-producer at any time during operation. When a small pressure is applied to the key 11, then a small pressure only is developed within the chest 20 and a soft tone is given out. To increase its power, it is only necessary to slightly increase the pressure upon its key 11. The air pressure within the chest 5 being increased as above defined acts upon the pallet 24 so that it will open to develop an increased pressure within the chest 20. If, on the other hand, decreased loudness is desired, a decrease of pressure on the key will accomplish it by minimizing the opening of the pallet 24.

It must be understood that it is not possible to bring the tone-producing pressure up to the theoretical maximum as indicated in the equation $p_2 \text{ max.} = p_1 \text{ max.} = p$. This is for the reason that the tone-producing pressure depends upon the relation of the respective inlet and outlet openings of the chest 20 in the same manner as pressure p_1 in chest 5 depends upon the relation between the openings 3 and 7. The inlet to chest 20 however can be made equal to the full size of the opening 22 whereas the outlet of chest 20 cannot be varied as it comprises the opening through the tone-producer. For this reason the ratio $\frac{O}{I}$ between the outlet and inlet of the chest 20 cannot in any event equal zero, and the tone-producing pressure cannot be brought up exactly to initial pressure even if pressure within chest 5 equals the initial pressure. It however will approach the initial pressure if the inlet to chest 20 is made as large as possible in proportion to its outlet through the tone-producer 21.

As above described, the pallet 24, disregarding its weight, is just in balance when its particular wind tunnel contains pressure and there is no pressure in the pipe 19. This fact suggests the danger that pallet 24 may not be entirely tight, and a certain amount of wind may pass through the tone-producer even if its particular key is not being played. This danger can be avoided by giving the pallet 24 a certain surplus of closing power while its key is not being operated. This can be accomplished by making the active surface of the movable bellows 26 larger than the surface of the pallet 24. Supposing this surface of the bellows is twice as large as that of the pallet 24 then the balance will take place when the pressures are as follows:

$$+p - 2p + 2p_1 - p_2 = 0,$$

or simplifying $p_2 = 2p_1 - p$. In other words, when $p_1 = O$, $p_2 = -p$, or the pallet 24 is pressed against its opening 22 with a surplus pressure which equals pressure p and therefore this

pallet may be maintained pressure tight. If we make $p_1 = \frac{p}{2}$ it follows that pallet 24 will again be in balance when the key 11 is pressed down to such an extent that p_1 has reached $\frac{1}{2}p$, that is to say when $\frac{O}{I}$ for chest 5 equals 1. Increasing p_1 , p_2 increases until p_1 equals p and p_2 equals p .

This difference of arrangement as compared with that first described results in the fact that the pallet 24 will not open as soon as the key is pressed down but will open only when it has been pressed to such an extent that p_1 has reached $\frac{1}{2}$ of the initial pressure p . This might make it awkward for the player to determine exactly what pressure of the key must be given to just make the tone-producer speak supposing that the key in its normal position rests on spring 14. This difficulty can then be overcome by giving the key a certain amount of movement before it reaches the spring 14 as shown in Fig. 1a. Then a very light pressure upon the key will press it far enough to develop a pressure within the chest 5 which will equal $\frac{1}{2}$ of the initial pressure supplied by the pump. At this moment, the key will just come into contact with the spring 14 and the position at which the pallet 24 will be in balance can be easily determined. Giving the key 11 a slightly increased pressure, pallet 24 will instantly open and its opening can be regulated to any desired degree by supplying and altering the pressure upon the key. The only difference therefore consists in the fact that only $\frac{1}{2}$ of the range of pressure p , between O and p can be used for the regulation of loudness of the tone-producers while the remainder of the range serves only in overcoming the surplus of the closing effect of the pallet 24 introduced by the increased size of the bellows 26.

Mechanisms for large instruments are diagrammatically shown in Figs. 3 and 4. Referring first to Fig. 3, it will be seen that the chest 5a in which the variable pressures controlling the intensity of tone are produced is in connection with a single bellows 31 through pipe 19a. The construction shown in Fig. 3 shows the mechanism for producing a given tone in three different registers or stops while a greater number of stops may be employed extending to the right of the three shown. The single bellows 31 is mounted in a separate tunnel 32 running in the same direction as the tone-producers of any given register. This tunnel 32 may be filled with compressed air from the source of supply. The movable member of the relay bellows 31 is mechanically connected with the pallet 33 by a suitable wire, this tunnel 32 opening into another tunnel 34. All the bellows 35 operated by one key 11a on the key

board are pneumatically controlled from the pressure developed within the single tunnel 34. The active surface of the pallet 33 is shown as being of the same size as the movable member of the bellows 31. Pallets 36 which admit air to the individual tone-producers as 21^a—29^a and 41^a may be of approximately one half the size as the bellows 35.

As above described, as soon as the pressure 10 within the chest 5^a is produced within the bellows 31, the pallet 33 will open admitting pressure to the tunnel 34. This pressure will exactly reach that in chest 5^a when it closes pallet 33. At that pressure, the bellows 35 15 will be expanded thus opening the pallets 36. This takes place when the respective chests 37 are not under any initial pressure. These chests 37 however must be under pressure when the tone producers associated therewith 20 are to be sounded. This, of course, takes place when pressure is admitted to the chambers 37 in any preferred manner, not shown. This pressure within chests 37 will not permit pallets 36 to open until the pressure within 25 the bellows 35 exceeds half the pressure within the chest 37. The pallets 36 at that pressure will open, the pressure controlling them being the pressure within the tunnel 34, which equals that within the chest 5^a.

30 The above mechanism, it might be assumed, would delay the speaking of the tone-producers. This, however, is not the fact for the reason that the large number of bellows 35 can be filled and exhausted much more 35 quickly through pressure within the tunnel 34 than would be possible through a single pipe such as 19^a.

If we assume that the active surface of the bellows 31 equals the active surface of pallet 40 33, then pressure p_2 within tunnel 34 will always equal p_1 within the chest 5^a. The pressure p_3 within the chests opening to the tone-producers will therefore vary with this pressure p_2 by reason of the action of the bellows 35 according to the equation $p_3 = 2p_2 - p_1$.

In other words, the pressure of the air admitted to the tone-producer can be regulated in the same manner as before, the only change being that an intermediate or relay 45 valve 33 is introduced. With this construction, any desired increase of tone power can be accomplished by merely introducing an increased pressure upon the key which causes pressure to be built up within the chest 5^a and 50 the tone-producers chests.

To decrease the tone power or intensity necessitates a separate device, which will enable the tunnel 34 to be exhausted to a greater or less extent. Releasing pressure upon the 55 key causes tighter closing of the pallet 33 so that unless exhausting means are provided, the pressure once established in tunnel 34 would be retained within this tunnel and bellows 35 would remain expanded as long as 60 this pressure was maintained. To overcome

this difficulty, the tunnel 34 is connected to the atmosphere through an opening 38 which is closed by a pallet forming the movable member of a bellows 39. The inside of this bellows is connected to a branch of pipe 19^a 70 indicated at 40. As soon as pressure is admitted to pipe 19^a, the pressure not only enters bellows 31 but also bellows 39 thus closing the opening 38. The pressure within the tunnel 34 constantly tends to open the port 38 75 and, as soon as the pressure in pipe 19^a drops slightly, its pressure is less than that within tunnel 34. The port 38 is therefore opened slightly until the air is exhausted from tunnel 34 and until the pressure within bellows 80 39 again equals it and closes the opening 38. The pressure to the tone-producers therefore is regulated both up and down in accordance with the pressure in chest 5^a.

By referring to Fig. 4 it will be seen that a 85 third method of obtaining varying loudness of the tone-producers by varying the pressure upon the keys has been provided. This method is operated by electro-magnetic means. Below each of the keys 11^b is located 90 a coil 50 forming the primary windings of a transformer to which alternating current may be supplied from any suitable source. Within this primary coil 50 is a secondary winding 51. On the key 11^b is mounted a piece of soft 95 iron 52, the position of which relative to the coils 50 and 51 varies with the different positions of the key. The effect of this iron 52 during playing is to vary the current flowing through the secondary winding 51. This is for the reason that the magnetic flux is varied with different positions of the iron 52. Wires 53 extending from the secondary winding 51 lead to the winding of a solenoid 54. From 100 the above it will be seen that variable current will be induced in this winding 54 due to the position of the key 11^b. The further key 11^b is depressed the further the iron piece 52 will enter the space within winding 51 and thus increase the current induced within this secondary winding.

Within the solenoid winding 54 is an armature 55 urged downward by a suitably mounted coiled spring 56. The effect therefore of 105 varying currents within winding 54 is to vary the position of the armature 55. Increased current within the solenoid 54 will tend to force the armature 55 upward against the pressure of the spring 56.

Attached to the armature 55 by means of 110 suitable wires are pallets 57 and 58 which control openings formed in a chest 32^b replacing chests 1^a and 32 shown in Fig. 3. This chest 32^b may be supplied with air under pressure from any suitable source. The effect of 115 varying the movement of the armature 55 and the pallets 57 and 58 is to vary the inlet and outlet openings of air tunnel 60. With the pallets 57 and 58 in the position shown in Fig. 4, air tunnel 50 which takes the place of chests 120 125 130

5 and 5^a shown in the above described figures is without air pressure. As soon as any pressure is placed on key 11^b and armature 55 is raised by the current in solenoid 54 pallets 57 and 58 open to an intermediate position. With the pallets in this intermediate position pressure will be built up in tunnel 60. This pressure will expand the bellows 31^b and open the pallet 33^b in the same manner as in the 10 form of the invention previously described. This pressure within bellows 31^b will be the same as that in tunnel 60 which pressure will be admitted to tunnel 34^b and to the tone-producer chests 20^b in the manner which will be understood from the description of the 15 other forms of the invention.

Tunnel 60 extends to the inside of a bellows 39^b the movable side of which presses against an opening 38 in tunnel 34^b. If then the current in solenoid 54 is weakened and the pallets 57 and 58 moved downward to reduce the pressure within tunnel 60^b the pressure in tunnel 34^b will be exhausted past bellows 39^b until the pressure in tunnel 34^b equals that in the 20 tunnel 60. Varying the positions therefore of the pallets 57 and 58 will permit varying the pressures within the tunnel 34^b either to increase or decrease the pressure supplied to the tone-producers 21^b, 29^b, 41^b, and so forth.

30 What I claim is:

1. A pneumatic action for organs comprising in combination, a plurality of keys, a plurality of tone-producers, means to supply air under pressure to said tone-producers, 35 pallets in said air supplying means, a pallet actuated by said key to vary the pressure within individual wind chests, bellows, conduits connecting said wind chests with their bellows, means connecting said bellows to their respective pallets whereby varying the 40 positions of said keys individually varies the positions of the bellows and said pallets and the pressure of air supplied to said tone-producers varies directly with the positions of said keys.

2. A pneumatic action for organs comprising in combination, a plurality of keys, a plurality of tone-producers, means to supply air under pressure to said tone-producers, 45 pallets in said air supplying means, actuated by said keys to vary the pressure within individual wind chests, bellows of larger area than said pallets, conduits connecting said wind chests with their bellows, means connecting said bellows to said pallets whereby varying the 50 positions of said keys varies the positions of the bellows and said pallets and the pressure of air supplied to said tone-producers varies directly with the positions 55 of said keys.

3. A pneumatic action for organs comprising in combination, a tone-producer, a wind chest therefor and directly associated therewith, a pallet positioned and opening there- 60 in, means to supply air under pressure to said

wind chest through said pallet, and means to vary the position of said pallet to vary the tone intensity of said tone-producer.

4. A pneumatic action for organs comprising in combination, a tone-producer, a wind chest therefor and directly associated therewith, a pallet positioned and opening therein, means to supply air under pressure to said wind chest through said pallet, and pneumatic means connected to said pallet to vary 75 its position and the pressure supplied to said tone-producer.

5. A pneumatic action for organs comprising in combination, a tone-producer, a wind chest therefor, a key for operating said tone-producer, a pallet positioned within and opening within said wind chest, means to supply air under pressure to said wind chest through said pallet, and pneumatic means connected to said pallet and actuated by said 80 key to vary the position of said pallet and the pressure supplied to said tone-producer.

6. A pneumatic action for organs comprising in combination, a tone-producer, a wind chest therefor, a key for operating said tone-producer, a pallet positioned within and opening within said wind chest to admit air under pressure thereto, pneumatic means connected to said pallet, and pallets actuated by said key to supply air under variable pressures to said pneumatic means whereby the pressure supplied to said tone-producer may be varied.

7. A pneumatic action for organs comprising in combination, a tone-producer, a wind chest therefor, a key for operating said tone-producer, a pallet positioned within and opening within said wind chest to supply air under pressure thereto, a bellows positioned within a portion of the air supplying means, 105 means connecting said pallet and bellows whereby pressure on said bellows holds the pallet in its closed position, and means to supply air under variable pressures to within said bellows to open said pallet and admit air under variable pressures to said tone-producer.

8. A pneumatic action for organs comprising in combination, a tone-producer, a wind chest therefor, a key for operating said tone-producer, a pallet positioned within and opening within said wind chest to supply air under pressure thereto, a bellows positioned within a portion of the air supplying means, 115 means connecting said pallet and bellows whereby pressure on said bellows holds the pallet in its closed position, means to supply air under variable pressures to within said bellows to open said pallet and admit air under variable pressures to said tone-producer, and means permitting air within said bellows to be exhausted when pressure on said key is reduced.

9. A pneumatic action for organs comprising in combination, a tone-producer, a wind 120

- chest therefor, a key for operating said tone-producer, a pallet positioned within and opening within said wind chest to supply air under pressure thereto, a bellows positioned within a portion of the air supplying means, means connecting said pallet and bellows whereby pressure on said bellows holds the pallet in its closed position, means to supply air under variable pressures to within 5
 10 said bellows to open said pallet and admit air under variable pressures to said tone-producer, and an auxiliary bellows connected with said first mentioned bellows and adapted to permit air in said first bellows to be exhausted when pressure on said key is reduced.
10. A pneumatic action for organs comprising in combination, a tone-producer, a wind chest therefor, a key for operating said 20 tone-producer, a pallet positioned within and opening within said wind chest to supply air under pressure thereto, a bellows positioned within a portion of the air supplying means, means connecting said pallet and bellows 25 whereby pressure on said bellows holds the pallet in its closed position, and means actuated by the key to supply air under variable pressures to within said bellows to open said pallet and admit air under variable 30 pressures to said tone producers.
11. A pneumatic action for organs comprising in combination, a plurality of tone-producers, individual wind chests therefor, pallets positioned and opening therein, means to supply air under pressure to said wind chests through said pallets, and unitary means to vary the positions of said pallets to vary the tone intensity of said tone-producers.
- 40 12. A pneumatic action for organs comprising in combination, a plurality of tone-producers, individual wind chests therefor, pallets positioned and opening therein, means to supply air under pressure to said wind 45 chests through said pallets, and unitary pneumatic means to vary the positions of said pallets to vary the tone intensity of said tone-producers.
13. A pneumatic action for organs com-
- prising in combination, a plurality of tone-producers, individual wind chests therefor, a key for actuating said tone-producers, pallets positioned and opening therein, means to supply air under pressure to said wind chests through said pallets, and unitary means actuated by said key to vary the positions of said pallets to vary the tone intensity of said tone-producers.
14. A pneumatic action for organs comprising in combination, a plurality of tone-producers, individual wind chests therefor, a key for operating said tone-producers, pallets positioned within and opening within said wind chests, means to supply air under pressure to said wind chests through said pallets, and unitary pneumatic means connected to said pallets and actuated by said key to vary the position of said pallets and the pressure supplied to said tone-producers.
15. A pneumatic action for organs comprising in combination, a plurality of tone-producers, keys for operating said tone-producers, individual wind chests therefor, pallets opening therein, means to supply air under pressure to said wind chests through said pallets, pneumatic means to vary the positions of said pallets to vary the tone intensity of said tone-producers, and electro-magnetic means to vary the pressure within the pneumatic means in accordance with the position of the keys.
16. A pneumatic action for organs comprising in combination, a plurality of tone-producers, keys for operating said tone-producers, individual wind chests therefor, pallets opening therein, means to supply air under pressure to said wind chest through said pallets, pneumatic means to vary the positions of said pallets to vary the tone intensity of said tone-producers, transformers associated with said keys, and electro-magnetic means actuated thereby to vary the pressure within the pneumatic means in accordance with the position of the keys.

In testimony whereof, I hereto affix my signature.

MAX MAAG.
